FLEXIBLE WINDOW CLOSURE

William D. Bayley, Springfield, Ohio, assignor
to The William Bayley Company, Springfield,
Ohio, a corporation of Ohio

Application January 29, 1936, Serial No. 61,412

10 Claims. (Cl. 189—64)

This invention relates to closure assemblies for ventilating areas in windows and in more particular to ventilating areas in metallic windows.

An object of this invention is to provide a closure assembly for windows wherein the guards across the window opening have been incorporated into the window structure.

Another object of this invention is to provide a closure provided with a flexible contact engaging the frame surrounding the closure.

Another object of this invention is to provide a closure for a ventilating area that is of less width than the distance between adjacent muntin bars.

15 Another object of this invention is to provide a closure for ventilating areas or windows that is cheap, efficient, durable and dependable, that makes good contact so as to protect the interior of the building from the elements.

20 Another object of this invention is to provide a unitary structure for the closure and its screen that may be inserted as a unit into the ventilating area.

25 With the above primary and other incidental objects in view, as will more fully appear in the specification, the invention consists of the features of construction, the parts and combinations thereof, and the mode of operation or their equivalents, as hereinafter described and set forth 30 in the claims.

Fig. 1 is a fragmentary front elevation of a window embodying my preferred modification.

Fig. 2 is a horizontal sectional view taken substantially on the line 2—2 of Fig. 1.

35 Fig. 3 is a vertical sectional view taken substantially on the line 3—3 of Fig. 1.

Fig. 4 is a sectional view of another modification.

Fig. 5 is a sectional view taken substantially 40 on the line 5—5 of Fig. 4.

Fig. 6 is a sectional view of another modification taken substantially on the line 6—6 of Fig. 7.

Fig. 7 is a sectional view taken substantially 45 on the line 7—7 of Fig. 6.

Fig. 8 shows a vertical sectional view of another modification.

Fig. 9 shows a perspective view of a modification similar to that shown in Fig. 1 with the closure removed.

50 Referring to the drawings the modification disclosed in Figs. 1, 2 and 3 utilize T-shaped muntin bars 20 transversely arranged, dividing the window into a plurality of spaces, some of which are glazed as shown at 22, leaving a group of spaces 55 vacant either entirely across from one muntin bar

to the other, or partially across the space between adjacent bars, as shown at 25.

By referring to Fig. 1 a space 23 has been left unglazed for a ventilating area. In order to protect the occupants of the building during inclement weather, it is desirable to provide a suitable closure for this ventilating area.

In the preferred embodiment, as shown in Figs. 2 and 3, the closure assembly including the frame 24 supporting the screen 26 upon one side and the sheet metal closure 28 upon the same side, is inserted as a unit into the ventilating area 23. The space 26 intermediate the muntin bars 20 and the frame 24 is preferably filled by a pliable, plastic or yieldable material, as the case may be. 10 In the present embodiment putty or cement has been shown. In the preferred embodiment the sheet metal closure 28 has been hinged at 30 and is biased into "open" position by a flat spring 32 normally holding the closure open. Resilient members 36 act as weather stripping between the closure 28 and the fixed parts bounding the ventilating area. The frame 24 is attached to member 70 best seen in Fig. 3, that is provided with a flange 38 against which the glazing 40 is 15 mounted. The stem of the muntin bar 20a is preferably provided with a saw-cut to receive the frame 24. 20

25 By releasing the closure chain 34 the closure 28 springs into "open" position under the influence of the spring 32. Whenever it is desirable to close the ventilating area this may be accomplished by pulling the chain 34, which may be held in "closed" position against the force of the spring 32 by a suitable latch not shown or by 30 any other suitable securing of the chain. 35

In the modification disclosed in Figs. 4 and 5 another type of metallic closure has been shown, wherein the closure is located along the confines of the muntin bars. This modification includes a U-shaped portion 41, extending along two sides of the window, arranged to hold the felt 42 or other yieldable material contacting the flanges 44 of the muntin bars 20 bounding the ventilating area. This U-shaped member 41 is comparatively rigid and forms a frame reinforcing the sheet metal closure 46. In the modification disclosed, the sheet metal closure is integral with the U-shaped member 41. It may be attached thereto by welding or in any other suitable manner.

50 As best seen in Fig. 4 the top and bottom edges of the closure 46 are formed into U-shaped portions. The vertical side portions are bent into U-shape arranged in hooked relation with the 55

flexible weatherstripping members 45 formed from suitable resilient metallic strips. As the closure abuts the inside of the flanges 44 and lies substantially within the confines of the T-bars, 5 it is not feasible to continue the muntin bars across the ventilating area. That being the case, suitable bars 48 extend across the ventilating area and are substantially aligned with the flanges 44 of the T-bars. These detention bars 48 which 10 prevent the free ingress and egress of human bodies through the window, may be aligned with the flanges of the T-bars, so as to simulate a window wherein the T-bars extend across the ventilating area. These guard bars or detention bars 48 may either be attached to the transversely arranged muntin bars bounding the ventilating area, or the detention bars 48 may be secured to the screen frame 50 located on the side of the flanges 44 opposite the closure member 46. The screen frame 50 may be held in position 15 by any suitable means. In the modification disclosed, the screen frame 50 has been soldered to the flanges 44.

In the modification disclosed in Figs. 6 and 7, 20 U-shaped channels supporting the felt 42 instead of being made from a unitary member is shown in the previous modification, is made from a pair of flanged members 60 and 62. The opposite ends of members 60 and 62 form another U-shaped channel 64 receiving the glazing 66. The flanges forming the U-shaped channel 64 extend in a direction parallel to the plane of the glazing 66 in contrast to the legs of the channel supporting the felt 42, which legs extend in a direction normal to 30 the plane of the glazing 66.

The closure assembly is pivotally mounted on a pair of pintles 80 supported in member 76 overlapping the flanges 44 and attached thereto by welding or in any other suitable manner. Reference 35 ring to Fig. 6 member 76 also forms the sill for the closure as a portion 78 overlaps the flange of the muntin extending along the bottom of the closure. Suitable bolts 82 passing through the web of the muntin bar may be tightened to 40 hold portion 78 in engagement with the web of the muntin bar. Instead of bolts, these parts may be welded together into a unitary structure.

In this modification a screen 84 is positioned intermediate the closure and the muntin bars of 45 the window. The portion 86 of the screen extending along the bottom thereof forms an abutment for the weatherstripping 42, so as to provide a seal above the sill. The sill of the window in this modification prevents the closure coming in 50 contact with the flange of the muntin bar extending along the bottom of the closure.

Referring to the modification shown in Figs. 8 and 9, the screen frame assembly projects through the ventilating area. The screen frame 60 90 is formed from angle bars having the flanges 92 projecting through the ventilating area and supporting the screen 94 suitably attached thereto. An abutment or snubber 96 attached to the lower flange 92 holds the screen frame at a 65 proper height. A stop 98 is arranged in hooked relation with the flange 44 to prevent the screen frame from removal bodily inwardly when the upper flange is held in position by a diagonally arranged screw 98.

70 The closure 100 pivotally attached by hinges 102, only one of which is shown, to the web of the muntin bar 20 extending along the bottom of the ventilating area, is held in closed position by a suitable latch arrangement 104 in a manner 75 similar to that shown in the other modifications.

The flanges 106 of the screen frame are arranged in spaced relation from the flanges 44 of the muntin bars. Weatherstripping members 110, substantially U-shaped in cross sectional area, are arranged in hooked relation with the flanges 106. One leg of each weatherstripping member 110 abuts the flange 44 and the other abuts the closure when in closed position. The weatherstripping members 110 are duo-functional in that in addition to providing weather tightness, these members provide a cushioned support for the screen frame. This assembly provides a very satisfactory closure assembly mountable into any space left vacant for ventilating area without the use of accurately milled parts, as the clearances may be sufficiently great to allow for almost unlimited tolerances in workmanship. 10 15

In the modification disclosed in Fig. 9, the metallic closure 28 has been removed. As may be clearly seen, the hooked shape edge 120 may be 20 hooked under hooked shaped stationary member 122 rigidly attached to the frame of the window.

From the above description it will be apparent that there is thus provided a device of the character described possessing the particular features 25 of advantage before enumerated as desirable, but which obviously is susceptible of modification in its form, proportions, detail construction and arrangement of parts without departing from the principle involved or sacrificing any of its advantages. 30

While in order to comply with the statute, the invention has been described in language more or less specific as to structural features, it is to be understood that the invention is not limited 35 to the specific features shown, but that the means and construction herein disclosed comprise the preferred form of several modes of putting the invention into effect, and the invention is therefore claimed in any of its forms or modifications 40 within the legitimate and valid scope of the appended claims.

Having thus described my invention, I claim:

1. A detention window assembly including a plurality of transversely arranged duo-functional 45 muntin and detention bars dividing the window into a plurality of spaces having portions thereof glazed leaving a ventilating area, having the bars extending across the same, said bars extending across the ventilating area having a notch cut 50 therein, and a closure assembly including a frame projecting into the notch to interlock the frame to the detention bars.

2. A window assembly including a plurality of transversely arranged bars dividing the window 55 into a plurality of spaces having a ventilating area of less width than the distance between two adjacent muntin bars and a closure for the ventilating area including a frame fixedly supported upon the muntin bars and including at least a 60 portion spanning adjacent muntin bars for supporting the glazing of the space partially used as a ventilating area.

3. A window assembly including a plurality of transversely arranged bars dividing the window 65 into a plurality of spaces some of which are glazed leaving a portion vacant as a ventilating area and a closure unit for the ventilating area including a screen frame and a metallic closure 70 movably mounted upon the screen frame, said closure and screen frame being insertable as a unit into the ventilating area, and means disposed intermediate the closure and the frame surrounding the ventilating area to seal the opening when the closure is in closed position. 75

4. A window including transversely arranged muntin bars dividing the window into a plurality of spaces some of which are glazed others partially glazed, the glazing extending part way 5 across the space between adjacent muntin bars, leaving the remaining portions of said partially glazed spaces vacant for ventilation and a closure unit for the ventilating area including a frame supported upon the muntin bars, said frame including a flanged member extending along the edge of the glazing, and means for sealing the frame, said means engaging the glazing to hold same in position.

5. A window including transversely arranged 15 muntin bars dividing the window into a plurality of spaces, some of which are glazed and at least two adjacent spaces each partially glazed, the glazing extending part way across the space between two adjacent bars leaving a portion of 20 each unglazed, said unglazed space being continuous except for at least one muntin bar extending across the same, a closure assembly for the ventilating area including a bar extending along the glazing bounding the ventilating area, said 25 member and the muntin bar extending across the ventilating area interlocking each other, there being a cut-away portion in at least one for receiving the other.

6. A closure assembly for a window having a 30 ventilating area bounded by a plurality of muntin bars, said closure assembly including a sheet metal frame, a screen attached to one side of the frame and a movable closure mounted on the sheet metal frame opposite the screen, said sheet 35 metal frame, screen and closure being insertable into the ventilating area as a unit, and means for securing said sheet metal frame in position.

7. A window assembly including a frame 40 surrounding a ventilating area, a closure for the ven-

tilating area insertable as a unit, said closure including a stationary and a movable frame mounted therein, and a flexible sheet material member disposed intermediate the frame surrounding the ventilating area and the stationary closure frame 5 for sealing the juncture between the frames.

8. In a window assembly, a plurality of transversely arranged muntin bars dividing the window into a plurality of spaces, some of which are partially glazed, leaving the balance of the partially glazed spaces vacant for ventilating area, 10 the muntin bars bounding three sides of the ventilating area and the glass of the partially glazed spaces forming the fourth side thereof, a movable closure for the ventilating area having a flexible 15 contact with at least some of the sides of the ventilating area, and a member supporting the closure, said member extending along one side of the ventilating area and effecting water tightness.

9. In a window assembly, a plurality of transversely arranged muntin bars dividing the window into a plurality of spaces some of which are glazed leaving at least one space partially glazed, the glazing terminating in spaced relation with 25 respect to one side of the space to form a ventilating area, a closure assembly for the ventilating area including a member extending along one side thereof, contiguous to the terminal of the glazing to provide water tightness.

10. In a window assembly, a plurality of transversely arranged bars dividing the window into a plurality of spaces, some of which are entirely glazed, others partially glazed having the glazing terminating in a free edge in spaced relation with 35 respect to one of said bars, a member extending along one side of the free edge, a movable closure engaging said member and a yieldable contact engaging the closure when in closed position.

WILLIAM D. BAYLEY. 40
